6 Claims. (Cl. 252—135)

The present invention relates to a method of producing detergents which consist of a mixture of alkali triphosphate with other components, which in part have detergent properties, and are characterized by the fact that for their production the alkali triphosphate is introduced into an aqueous solution or suspension of all other components or at least a part thereof, and the detergent batch treated in known manner with heat.

Detergents of this type have been known for a long time, but their preparation afforded difficulties insofar as in the case of addition of alkali triphosphate which is free of water to a greater or lesser extent to the detergent batch—also called slurry—the phosphate withdraws the water from the latter so as thereby to become hydrated in faster or slower manner to $\text{Na}_5\text{P}_3\text{O}_{10} \cdot 6\text{H}_2\text{O}$.

Together with this hydration, the viscosity of the slurry increases which has an extremely detrimental effect on the further processing, as for instance in a spray drying process.

It was attempted by increased addition of water to reduce the viscosity of the mixture. This had the disadvantage that in order to evaporate the excess water there was now required a correspondingly large amount of energy which both increased the cost of the process and reduced the capacity of the drying installations.

As long as tripolyphosphate-pyrophosphate mixtures were incorporated in the slurries, the increase in viscosity occurred only to a reduced extent since the pyrophosphate contained in the tripolyphosphate-pyrophosphate mixtures exerted a liquefying action upon the stirring of a detergent batch (slurry). However, with this method of procedure, a considerable drop in the calcium-combining power must be tolerated, since the calcium-combining power of pyrophosphate is only one-third of the calcium-combining power of sodium tripolyphosphate, and for this reason the use of pure tripolyphosphate is preferred in modern detergents.

It was also endeavored, by using a substantially or completely anhydrous triphosphate to maintain the slurry at a suitable consistency; however, this method also has considerable disadvantages. It is known that anhydrous alkali triphosphate, when stored and transported under normal conditions, absorbs a slight amount of moisture from the air, and passes to a corresponding extent into the hydrated form. This slight water absorption is already sufficient to make the phosphate unsuitable for the known method. It is therefore necessary to heat this salt again to a high temperature shortly before its use up to several hours in order to obtain it in anhydrous form. In this way, this method is made expensive and becomes cumbersome.

It is also known to control the viscosity of the slurries by the introduction of tripolyphosphate mixtures of phase I and of phase II. The preparation of such mixtures having a narrow range of the ratio of phase I to phase II results, however, in increased requirements in connection with the manner of manufacture of the phosphate, and furthermore, the effect of these mixtures is only relatively slight.

Now we have found on basis of extensive investiga-

2

tions, that all of these disadvantages can be eliminated by adding small amounts of calcium compounds to the slurry. A quantity of 0.1 to 2%, and preferably 0.2 to 1% of calcium ions, calculated on the triphosphate employed, is sufficient to influence the viscosity of the detergent in the desired manner.

It is particularly advantageous if the calcium compound is added to the alkali triphosphate, and especially in dry form.

It was very surprising to find that specifically calcium ions produce the observed effect, especially as the alkali triphosphate in a detergent has the mission of eliminating the so-called calcium hardness of the water by combining, in the form of a complex, with the calcium ions present in the water. For this reason, it may appear paradoxical to add Ca-ions from the start to a substance which combines with calcium. Experiments however, showed that the effective quantity of Ca of 0.1 to 2% of the alkali triphosphate is negligibly small as compared with the amount with which the triphosphate is able to combine.

The calcium-combining power of a good sodium tripolyphosphate is 11.5 grams ca per 100 grams $\text{Na}_5\text{P}_3\text{O}_{10}$. 100 grams of triphosphate therefore combine with 11.5 grams of Ca. If for instance 0.27% Ca in the form of salts, calculated on the amount of triphosphate, is added to the slurry, the triphosphate loses 2.3% of its original calcium-combining power. This slight decrease is not as important as the disadvantages involved in the measures previously carried out to reach the same goal.

Aside from the aforementioned disadvantages of the known methods, when a large excess of water is used, a part of the alkali triphosphate is hydrolyzed during the course of the drying process, and the calcium-combining power of the detergent is thereby considerably impaired.

As calcium compound, $\text{Ca}(\text{OH})_2$ is preferably employed since this product is of low price and can be obtained free of iron; it does not absorb water upon lengthy storage and does not introduce foreign anions. However, other compounds of calcium are also suitable, such as calcium sulfate or any desired mixtures of Ca salts.

The direct measurement of the viscosity of a slurry containing tripolyphosphate can be carried out by means of a plastograph of the Brabender Company. With this plastograph, the action of a tripolyphosphate on the viscosity of the slurry can be directly measured and recorded as a function of time for a given slurry and constant temperature. The degrees of consistency are measured (1000 degrees of consistency = 0.2 mkg.). The moments of rotation produced on the rotatably supported motor housing by the kneading resistance are transferred to a scale and from there to a recorder.

The following examples serve to illustrate the invention but they are not intended to limit it thereto. All percentages are to be understood as percentages by weight.

The examples clearly show that without the addition of calcium to the slurry, the viscosity of the latter, expressed in scale divisions of a plastograph, only a few minutes after the introduction of the triphosphate reaches values which are several times greater than in the case of the addition of calcium.

Example 1

65 There was used a slurry of the following composition:

	Grams
Sodium triphosphate	400
Tetrapropylene benzene sulfonate (50%)	400
Na_2SO_4	100
Sodium silicate	50
Magnesium silicate	20

Methyl cellulose ----- 20
 H_2O ----- 190
 at a temperature of 60° C.

Time in minutes after completion of the introduction	Consistency in scale graduations of a plastograph	
	Without addition of Ca-compounds	With 0.2% $Ca(OH)_2$
1	100	100
5	340	90
10	740	90
20	1,060	90
30	1,260	150
40	1,340	250
50	1,360	350
60	1,340	450

Time in minutes after completion of the introduction

Time in minutes after completion of the introduction	Consistency in scale graduations of a plastograph		
	Without addition of Ca-Compounds	With 0.2% $Ca(OH)_2$	With 0.5% $Ca(OH)_2$
1		30	50
10		670	100
20		700	340
30		680	450
40		640	520
50		630	530
60		630	520

Example 2

The same slurry was used as in Example 1, at a temperature of 80° C.

There was used a detergent of the following composition:

Time in minutes after completion of the introduction	Consistency in scale graduations of a plastograph			
	Without addition of Ca-compounds	With 0.2% $Ca(OH)_2$	With 0.5% $Ca(OH)_2$	With 1% $Ca(OH)_2$
1	150	100	100	50
10	130	50	110	110
20	420	60	100	100
30	850	250	100	100
40	980	520	160	200
50	1,050	680	340	320
60	1,050	740	700	500

Example 3

A slurry of the following composition was used:

	Grams	40
Sodium triphosphate -----	400	
Tetrapropylene benzene sulfonate (50%) -----	400	
Na_2SO_4 -----	100	
Sodium silicate -----	50	
Magnesium silicate -----	20	
Methyl cellulose -----	20	
H_2O -----	290	

at a temperature of 80° C.

Time in minutes after completion of the introduction	Consistency in scale graduations of a plastograph		
	Without addition of Ca-Compounds	With 0.2% $Ca(OH)_2$	With 0.5% $Ca(OH)_2$
1	40	40	20
10	640	200	140
20	600	360	280
30	550	350	380
40	540	340	420
50	520	340	420
60	500	280	410

at a temperature of 60° C.

Time in minutes after completion of the introduction	Consistency in scale graduations of a plastograph		
	Without addition of Ca-Compounds	With 0.2% $Ca(OH)_2$	With 0.5% $Ca(OH)_2$
1	50	50	50

	Without addition of Ca-Compounds	With 0.2% $Ca(OH)_2$	With 0.5% $Ca(OH)_2$
1	40	40	20
10	640	200	140
20	600	360	280
30	550	350	380
40	540	340	420
50	520	340	420
60	500	280	410

Example 4

There was used a slurry of the following composition:

	Grams	65
Sodium triphosphate -----	400	
Tetrapropylene benzene sulfonate (50%) -----	200	
Fatty alcohol sulfate (65%) -----	150	
Na_2SO_4 -----	100	
Sodium silicate -----	50	
Magnesium silicate -----	20	
Methyl cellulose -----	20	
H_2O -----	334	

at a temperature of 80° C.

Time in minutes after completion of the introduction

Time in minutes after completion of the introduction	Consistency in scale graduations of a plastograph		
	Without addition of Ca-Compounds	With 0.2% $Ca(OH)_2$	With 0.5% $Ca(OH)_2$
1	40	40	20
10	640	200	140
20	600	360	280
30	550	350	380
40	540	340	420
50	520	340	420
60	500	280	410

75 at a temperature of 60° C.

Example 6

There was used a slurry of the following composition:

	Grams	75
Sodium tripolyphosphate -----	400	
Tetrapropylene benzene sulfonate (50%) -----	300	
Fatty alcohol sulfate (65%) -----	156	
Na_2SO_4 -----	100	
Sodium silicate -----	50	
Magnesium silicate -----	20	
Methyl cellulose -----	20	
H_2O -----	20	

The above slurry was examined with an addition of water of 284 grams, 384 grams and 484 grams and compared with an identical slurry containing 284 grams of H₂O and different additions of Ca-salt.

with merely a part of the detergent composition components, and thereafter the resulting mixture is mixed with the remaining components of the detergent composition.

4. The method of claim 1 wherein the calcium salt

Time in minutes after completion of the introduction	Consistency in scale graduations of a plastograph					
	Slurry 1 +284 g. H ₂ O	Slurry 1 +384 g. H ₂ O	Slurry 1 +484 g. H ₂ O	Slurry+284 g. H ₂ O		
				With 0.1% Ca(OH) ₂	With 0.25% Ca(OH) ₂	With 0.5% Ca(OH) ₂
1	50	30	40	50	50	50
5	520	440	200	160	100	60
10	700	560	415	350	120	60
20	780	580	455	530	180	100
30	825	570	380	585	260	200
40	825	555	400	640	320	260
50	840	550	375	670	370	330
60	820	530	380	660	410	380

¹ Without addition of Ca-salt.

It is clear from this that a slurry containing 284 g. H₂O+0.5% Ca(OH)₂ corresponds in viscosity to a slurry containing 484 g. H₂O. In this case, 13% water could be saved.

We claim:

1. In the method of producing detergent compositions consisting essentially of alkali metal tripolyphosphates selected from the group consisting of sodium tripolyphosphate and potassium tripolyphosphates, and other conventional detergent components from an aqueous slurry containing the alkali metal tripolyphosphates and at least a part of said other detergent components, the improvement which comprises adding to the slurry 0.1 to 2.0% by weight of a calcium salt which ionizes substantially complete in the slurry, the amount of the calcium salt being calculated on the amount of alkali metal tripolyphosphate present in the slurry, and spray-drying the resulting mixture.

2. The method of claim 1 wherein the calcium salt is added to the slurry in an amount of 0.2 to 1% by weight, calculated on the amount of alkali metal tripolyphosphate present in the slurry.

3. The method of claim 1 wherein the alkali metal tripolyphosphate and the calcium salt are mixed initially

is selected from the group consisting of Ca(OH)₂ and CaSO₄·2H₂O.

5. The method of claim 1 wherein the calcium salt is added to the slurry in admixture with the alkali metal tripolyphosphate.

6. The method of claim 4 wherein calcium salt is admixed while dry with the alkali metal tripolyphosphate.
